CLAIM

The ornamental design for a container for transporting photographic film cassettes, as shown and described.

DESCRIPTION

FIG. 1 is a perspective view of my invention of a container for transporting photographic film cassettes;

FIG. 2 is a top plan view of the container of FIG. 1;

FIG. 3 is a side elevational view of the container of FIG. 1, the opposite side elevational view being a mirror image thereof;

FIG. 4 is an end elevational view of the right-hand side of the container of FIG. 3;

FIG. 5 is an end elevational view of the left-hand side of the container of FIG. 3; and,

FIG. 6 is a bottom plan view of the container of FIG. 1.
